UNITED STATES PATENT OFFICE.

FREDERICK E. KELSEY, OF CLEVELAND, OHIO.

CIGAR-BUNCHING MACHINE.

SPECIFICATION forming part of Letters Patent No. 281,517, dated July 17, 1883.

Application filed December 28, 1882. (No model.)

To all whom it may concern:

Be it known that I, FREDERICK E. KELSEY, of Cleveland, in the county of Cuyahoga and State of Ohio, have invented certain new and useful Improvements in Cigar-Bunching Machines; and I do hereby declare the following to be a full, clear, and exact description of the invention, such as will enable others skilled in the art to which it pertains to make and use the same.

My invention relates to improvements in cigar-bunching machines; and it consists in certain features of construction and combination of parts, hereinafter described, and pointed out in the claims.

In order that my invention and the uses for which it is designed may be clearly understood, I will hereby describe the manufacture of two kinds of cigars; but first I will state that the tobacco that is to form the central part and bulk of the cigar is called the "filler." The portion of tobacco-leaf that is wrapped around the filler is called the "binder," and the next and outer covering is the wrapper. The end of the cigar that is to be lighted is called the "tuck," and the end that is held in the mouth is called the "head." In one class of cigars what is known as the "longer" filler is used. This consists of pieces of leaf tobacco broken into the required length and carefully rolled up and held in position by the aforesaid binder and wrapper. Much care must be given to the filler, to the end that it may be evenly laid and in due proportion to give the required shape, and also that it may be free from inequalities, in order that it may smoke freely and burn evenly. After the tobacco has been selected for this purpose there will remain a large percentage of it that is too short, or is in some other way unsuitable for this kind of filler. To utilize these fragments they are reduced to a uniform small size and called "scraps," and known as "scrap" or "short" filler. A device for placing the binder around the filler and forming it into the proper shape for a cigar is called a "bunching-machine." In making this kind of cigar by hand, when scrap-filler is used, much difficulty is encountered in distributing and retaining the cut filler in such quantity and position as to give the desired size and shape to the cigar; also, the edge

of the binder is liable to be thrust into the filler or to be doubled back on itself; or a portion of the filler may be scattered between the 55 folds of the binder, any of which accidents injure the cigar, and are also liable to injure the temper of the man who is smoking it.

Many inefficient devices have been used for making this kind of cigar. In some of these 60 devices rollers have been used, similar in some respects to the rollers that I use in my device; but I have no knowledge of any such device that has given satisfaction to the trade, or that has been in general use previous to my invention.

In the drawings, Figure 1 is a side elevation, showing a supporting-frame and rollers, and the spur-gearing, pulley, and clutch for operating the same, and, on the left-hand side, 70 showing the device for operating and adjusting a stop that extends into the chamber that is surrounded by the rollers. Fig. 2 is a vertical longitudinal sectional view, showing the pointed stops that operate in the central chamber, and the three back rollers, and also the bottom roller, in section. Figs. 3 and 4 are end views, the former showing the top rollers open to receive the filler; also showing the devices for weighing and discharging the filler 75 into the central chamber of the rollers, and the device for opening and closing the top rolls, and showing, on the left hand, a flexible table, on which the binder or wrapper is placed to be fed into the machine. Fig. 4 80 shows the top rolls closed. Fig. 5 is a vertical longitudinal view of a sizing-box, in which the filler is weighed and adjusted to give the proper shape to the cigar, and, by means of attached levers, the said filler is discharged into 85 the aforesaid chamber of the rollers. Fig. 5 shows the top rolls closed. Fig. 5 is a vertical longitudinal view of a sizing-box, in which the filler is weighed and adjusted to give the proper shape to the cigar, and, by means of attached levers, the said filler is discharged into 90 the aforesaid chamber of the rollers.

In Fig. 1, A represents a supporting-frame, with the standards *a a* and *a'*, the two former supporting all of the rollers except the two top rollers, and supporting, also, one end of 95 the driving-shaft B. The other end of said shaft is supported by the standard *a'*. The said shaft is provided with a driving-pulley, to which is attached the clutch *b*. The said clutch is provided, in the usual manner, with a lever for operating the same, and to one end of the lever is attached the spring *a²* for holding the clutch open, and at the other end said lever has a hole, *b²*, whereby a rod may be at-

tached leading to the treadle on the floor, whereby the clutch may be operated and the rollers stopped or started by the foot of the operator.

5 To the shaft B is also attached a small pinion, that engages the like pinions, b', that are attached, respectively, to each of the rollers, by means of which the rollers move simultaneously and in the same direction. These 10 rollers are placed in such relative position to each other that they inclose a central space or chamber of suitable size for forming a cigar. This chamber is shown in Fig. 2, and also in the end views, Figs. 3 and 4. In this chamber, as shown in Fig. 2, are two pointed stops, C and C'. The latter is formed on the end, and is a continuation of the driving-shaft B.

The stop C terminates in a spindle running through the block c in such manner that while 20 the said stop is free to revolve on its spindle it is supported and controlled endwise by the movements of the block c. The said block has its support in a thimble, c'', that is a part of the standard a. The said block is provided 25 with the adjustable ring c', that acts as a stop against the said thimble, and controls the distance that the stop C extends into the said chamber, which in turn gages the length of the cigar. The ring c' is connected with the 30 bent lever D, which in turn is connected with and is operated by a treadle. The spring d holds the parts in position with the stop C thrust into the said chamber, while the stop d' allows the stop C to be drawn back only far 35 enough to disengage the cigar and allow it to be removed from the machine.

In Fig. 4 it will be seen that the arms a' are continuations downward of the standards a, and that to these arms are pivoted at their 40 lower ends the arms G and G', and that these arms support the top rollers, E and E'. The arms G and G', pivoted on arms a', are of course attached alike to both ends of the said top rollers.

45 In Fig. 4 is shown the orifice O in the standard a, through which the block c, Fig. 2, operates. The rollers, as shown in Fig. 4, are in position to compress and roll the cigar into proper shape.

50 In Fig. 3 the top rollers are shown as opened to receive the filler, and also is shown the device for opening and closing these rollers E and E'. This device consists of the levers H, fulcrumed on and attached to the rod h, and 55 to which are attached the bosses h' and the pins h''.

I will here say that as there are arms G and G' attached to each end of the top rollers, as aforesaid, so there are two levers, H, each of 60 which is attached to its respective end of the rod h.

65 It will be seen in Fig. 4 that when the rollers are closed the pins h'' engage parallel seats on the arms G and G', and hold the arms and attached rollers in position. When the levers are pressed downward, the said pins are forced from their seats, and at the same time the boss

h' is pressed between the said arms, forcing them apart, as shown in Fig. 3. The levers terminating in the handle H' being also attached to the rod h, the rollers may easily be opened and closed by simply moving the said handle.

In Fig. 5 is shown an enlarged sectional view, and in Fig. 3 are end views of the sizing box I. This box is made of suitable length and width for passing between the opened rollers, as shown by the dotted lines in Fig. 3. It is also made of suitable depth to contain the amount of filler required for a cigar. This 80 box may be made in a variety of ways, but I prefer one similar to that shown. This has a false bottom or plunger, i, and has attached the rod i', terminating in a knob for pressing upon with the hand. One or both of the sides 85 open partially on pivots j', as shown at J, giving a wider space for introducing the filler. To the pivots j' is connected a spring, j, which turns said pivots to return the leaf J toward its original position. To the said box is attached the lever L, which is pivoted to the standard l, located in such position as to guide the box between the rollers E and E'. When the said box is in position for receiving the 90 filler, it rests upon the pointer-rod k', which in turn rests upon the balance-beam K, which is fulcrumed at k, and is provided with the weight k''. This weight may be adjusted on the beam K to give any desired amount of filler that is required for a cigar, and by this means the 95 cigar may be made uniform. After the filler is placed in the box the side J is pressed in upon the filler and holds it in place, while the box is by the hand turned to an inverted position between the rollers, as aforesaid. Next, 100 by pressing upon the knob of the rod i' the plunger i is made to discharge the filler into the chamber aforesaid. A spring, as at i'', or two springs, as at i', or all of them, may be employed to return the plunger to its position; 105 or the springs may be omitted and the plunger left to fall back by gravity when the box is turned back to its first position.

It will be seen that the rollers E and E', when 110 opened, form, with the rollers below, a deep chamber to receive the filler, for the said filler before it is pressed by the rollers is quite bulky. The top rollers are now closed, and the train of rollers set in motion, compressing and rolling the filler into the proper shape. Next, the 115 binder is placed on the table F and passed along until it is engaged by the fluted roller e and drawn by it into the machine, where it is wrapped around the filler. The table F is made elastic, and has a slight play between the roller e and the next lower roller, so that it may bend down slightly when thick places in the binder are encountered, and the said 120 table also extends far enough between the rollers e and e' to protect the binder from the latter, as the motion of the top of this roller is outward.

The stops C and C', that, as before mentioned, are adjusted to gage the length of the

cigar, are made pointed, so as to extend a short distance into the respective ends of the filler, and are so shaped that the respective cavities left in the ends of the filler will admit of the 5 filler being compressed at the ends and formed into the desired shape.

I do not limit myself to the precise construction herein described, as in different parts of the device other means for obtaining the 10 same result will readily be suggested to a competent mechanic.

What I claim is—

1. In a cigar-bunching machine consisting, essentially, of a system of rollers, an elastic 15 table upon which the wrapper or binder may be spread out, the said table extending between two of the rollers, substantially as and for the purpose shown and described.

2. The combination, with a series of rollers, 20 of two upper rollers arranged to open and close, the levers G G', arranged in pairs at the opposite ends of said upper rollers and pivoted thereto, and means for operating said pairs of levers simultaneously, substantially as 25 described.

3. The combination, with the upper rollers of a series of cigar-forming rollers, of the pivoted levers G G', supporting said upper rollers, the lever H, provided with the boss h', 30 arranged between the said levers, and the pins h² h², arranged to compress the said levers, and suitable means for operating the said lever H, substantially as described.

4. The combination, with the two upper rollers, E E', and with levers H H' and levers G G', diverging at their upper ends and supporting said rollers, having the boss h' arranged between them, and the pins h² h², arranged

opposite the outer edges of said levers, of the shaft h, and the lever H', substantially as 40 described.

5. The combination, with the series of cigar-forming rollers having the two upper rollers arranged to open laterally, of the sizing box I, supported by the lever L and post l, arranged to swing forward and downward and discharge its contents into the space inclosed by the rollers, substantially as described. 45

6. The sizing-box mounted on a pivoted arm, having the upper portion of one or both 50 of its sides pivoted, and provided with suitable means for automatically returning said pivoted side or sides toward their original positions, substantially as described.

7. The combination, with the sizing box 55 mounted on a pivoted arm and adapted to swing outwardly with its open end upward for receiving the filler, of the spring-retracted plunger and suitable means for operating the said plunger to discharge the filler, substantially as described. 60

8. The combination, with the sizing box arranged to stand normally with its open end upward, and also mounted on a pivoted arm to swing forward and over the rollers for discharging the filler, of a scale-beam and its co-operating devices, arranged to receive the weight of said box when it is swung outwardly to receive the filler, substantially as described. 65

In testimony whereof I sign this specification, in the presence of two witnesses, this 8th day of December, 1882. 70

FREDERICK E. KELSEY.
